UNITED STATES PATENT OFFICE.

PEARLY M. CLEVENGER, OF SOUTH ENGLEWOOD, MISSOURI, ASSIGNOR TO VICTOR L. PHILLIPS, OF KANSAS CITY, MISSOURI.

POCKET KEY CARRIER.

Application filed September 18, 1922. Serial No. 588,831.

To all whom it may concern:

Be it known that I, PEARLY M. CLEVENGER, a citizen of the United States, and resident of South Englewood, county of Jackson, 5 State of Missouri, have invented a certain new and useful Improvement in Pocket Key Carriers, of which the following is a complete specification.

This invention relates to pocket key carriers of that class in which the keys are enclosed by a leather case, and more especially to carriers wherein each key can be rotated independently of the other keys and the case, and my object is to produce an 10 efficient key carrier of this character which is of simple, strong, durable and inexpensive construction.

To this end, the invention consists in certain novel and useful features of construction and combinations of parts as hereinafter described and claimed; and in order that it may be fully understood, reference is to be had to the accompanying drawing, in which:—

25 Figure 1 is a perspective view of a key carrier embodying the invention, with the case open and one of the keys extracted therefrom and ready for use;

30 Figure 2 is a top plan view of the device in closed condition;

Figure 3 is an enlarged vertical section taken on the line III—III of Figure 1;

Figure 4 is a section taken on the line IV—IV of Figure 3;

35 Figure 5 is a detail perspective view of the anchoring plate of the device; and

Figure 6 is an enlarged elevation to show the connection between the key hook or clamp and the chain for suspension from the 40 anchoring plate.

Referring to the drawing in detail, 1 indicates a key case preferably flexible and of leather, and consisting of a body portion and two foldable portions or flaps 2 and 3 45 adapted when folded over the body portion and overlapping each other to be fastened together by the conventional snap button clasp, or any equivalent device.

50 Arranged against the inner side and near the upper end of the body portion is a metal holder plate 4, the same being secured in place by suitable rivets 5 or the like. Said plate is formed near its upper edge and parallel therewith with a semi-cylindrical or

outwardly-bowed portion 6, and is provided 55 in said portion and in the upper edge with a series of transverse kerfs 7. Arranged in endwise alignment within the semi-cylindrical portion 6 and adapted for pivotal or rocking operation therein in transverse 60 planes, are hollow pins or heads 8, and extending through the kerfs and into said pins or heads respectively, are the uppermost pin links 9 of a series of chains, the alternate 65 links being of spherical form as at 10 and capable of turning or rotating on and transversely of the links 9. The uppermost links are provided with heads 11 within the hollow pins or heads 8 as shown most clearly by Figures 3 and 4, and are incapable of 70 swivel movement therein, it being noted however that all of the members or links 10 are capable of swiveling or turning on the links 9 to which they are respectively attached, so that the respective keys herein- 75 after identified, are capable of rotation independently of each other and of the case and holder plate 4.

A snap hook 12 or the like is adapted for use with each of the flexible swivel chains 80 above described, and each snap hook is provided at its upper end with a loop 13 fitting around the bottom link 10 of its respective chain, the loop being slotted as at 14 to accommodate pivotal movement of the hook 85 relative to the end of its respective chain. Each of the snap hooks is adapted to receive and carry one or more keys 15, as indicated in Figure 1, and when a key is desired for use, the case is opened and the particular 90 key extracted from the case as indicated in Figure 1, the respective head or pin 8 turning in the cylindrical portion 6 of plate 4 to permit the parts to be arranged as above referred to. The key can now be inserted 95 in a lock and turned or rotated freely and entirely independent of the case and plate 4, as the chain members 9 and 10 have relative rotative action and eliminate the necessity for having the chain bear a swivel relation 100 to the plate 4 at the point of connection therewith.

From the above description it will be apparent that the device embodies the features of invention set forth as desirable in the 105 statement of the object of the invention, and that it may be modified in minor particulars without departing from the principle of

construction and mode of operation involved or from the spirit and scope of the appended claim.

I claim:

- 5 In a pocket key carrier, a foldable case, a metal holder plate secured to the inner side of the case and provided with transverse kerfs and with a cylindrical portion, chains composed of alternately arranged pin
- 10 links and spherical links swiveled together, the uppermost pin link extending through

said kerfs respectively, cylindrical heads within the said cylindrical portion of the holder plate and secured to the said uppermost pin links of the chains respectively, ¹⁵ and snap hooks having circular slotted heads for swivel and pivotal movement in a single plane with the terminal spherical links.

In witness whereof I hereunto affix my ²⁰ signature.

PEARLY M. CLEVENGER.
